(57) **CLAIM**

The ornamental design for a multi-function pore extractor, as shown and described.

DESCRIPTION

FIG. 1 is a top-front-left perspective view of a multi-function pore extractor showing our new design;

FIG. 2 is a bottom-rear-right perspective view thereof;

FIG. 3 is a front elevational view thereof;

FIG. 4 is a rear elevational view thereof;

FIG. 5 is an enlarged top plan view thereof;

FIG. 6 is an enlarged bottom plan view thereof;

FIG. 7 is a right elevational view thereof; and,

FIG. 8 is a left elevational view thereof.
